(57) **CLAIM**

We claim the ornamental design for a passenger car, as shown and described.

DESCRIPTION

The file of this patent contains at least one drawing executed in color. Copies of this patent with color drawing(s) will be provided by the Patent and Trademark Office upon request and payment of the necessary fee.

FIG. 1 is a front perspective view for a "passenger car" showing our new design,

FIG. 2 is a rear perspective view thereof,

FIG. 3 is a front view thereof,

FIG. 4 is a rear view thereof,

FIG. 5 is a right-side view thereof,

FIG. 6 is a left-side view thereof,

FIG. 7 is a top view thereof,

FIG. 8 is a front view thereof, wherein the highlighted orange area represents a translucent surface of the headlights,

FIG. 9 is a rear view thereof, wherein the highlighted orange area represents a translucent surface of the taillights; and,

FIG. 10 is a top view thereof, wherein the privacy glass is in a thick black finish and shaded as a black mass.
